BOOK MATCH BAR

Maurice Polacsek, Brooklyn, N. Y.

Application August 31, 1934, Serial No. 742,206

1 Claim. (Cl. 206—29)

This invention relates to new and useful improvements in match packages and has more particular reference to a book match bar, strip or roll.

5 It is a general custom to manufacture books of matches with twenty matches in each book. It is also general custom to sell packages of cigarettes containing 20 cigarettes. When a purchaser buys a package of cigarettes he is given 10 one book of matches. While the number of cigarettes and matches correspond, it is found in practice that quite often the matches are blown out by the wind and it requires more than one match to light a cigarette. For this reason a 15 demand exists for additional matches. Persons generally ask for such additional matches gratis. It is an object of this invention to so construct a book match bar, roll or strip that portions thereof may be readily detached and any small 20 quantity of matches be thus obtained to be given away.

It is also an object of this invention to provide the homes with match bars from which any small portion or quantity of matches may be detached 25 for use.

Still further the invention particularly proposes the construction of an article as mentioned which is characterized by a unit of match stock, a cover strip for the match stock, and manually segregateable means dividing off detachable sections 30 of said match stock and cover, whereby one or more sections may be detached as a unit.

Still further the invention proposes the teaching of the use of score lines, grooves, dents, perforations and similar weakened or cut portions 35 as constituting the means whereby the divided off sections mentioned in the previous paragraph may be readily detached.

Still further the invention contemplates the 40 use of perforations, cuts, scorings and the like arranged in such a manner that the amount of matches may be measured.

The invention further contemplates the provision 45 of thin paper or similar means holding separate sections of books of matches together in a strip, bar or roll so that various sections may be detached when desired.

A further object of this invention is the construction of a device as mentioned which is simple and durable and which can be manufactured 50 and sold at a reasonable cost.

For further comprehension of the invention, and of the objects and advantages thereof, reference will be had to the following description and 55 accompanying drawing, and to the appended

claim in which the various novel features of the invention are more particularly set forth.

In the accompanying drawing forming a material part of this disclosure:—

Fig. 1 is a fragmentary perspective view of a 5 book match bar constructed according to this invention.

Fig. 2 is a perspective view of one of the sections of Fig. 1 detached.

Fig. 3 is a fragmentary view of Fig. 1 shown 10 with the cover open.

Fig. 4 is an edge elevational view of Fig. 3 looking from the left hand side.

Fig. 5 is a fragmentary perspective view similar to Fig. 1 illustrating a modification of the invention. 15

Fig. 6 is an elevational view of Fig. 5 shown with the cover open and looking on the inner side.

The book match bar, according to this invention, comprises a unit of match stock 10 associated with a cover strip 11 for covering the match stock. The match stock comprises a continuous base portion 10^a from which groups of matches 10^b project. These groups may be groups of five, 25 ten or any denomination desired. The groups are separated from each other by small spaces as clearly illustrated in Fig. 3. The cover 11 has its lower end turned up across the base strip 10^a of the match stock and is secured in this position 30 with staples 12, one staple for each match section. The outer side of the upturned portion is formed or supplied with chemical substance 13 upon which the matches may be struck to ignite them. 35

The feature of this invention is the provision of manual segregateable means dividing off detachable sections of the match stock and cover whereby one or more sections may be detached as a unit. This means comprises niches 14 arranged 40 upon the bent edge of the cover at the proper spaces to coincide with the match sections and in line with perforations 15 and, or scoring lines 16. The book match bars may also be without niches 14. It is preferred that the scoring lines 45 16 be arranged to include several groups or sections of matches so that the dividing off of the standard size of match package will be very easy. The intermediately segregateable means constitutes the perforations 15 which divide these main 50 portions into smaller sections. The sections may be segregated with the match package bar in the closed position as illustrated in Fig. 1. It is merely necessary that stresses be placed upon the niches 14 and the section or sections may be torn off. 55

Each small detached section may be used as a book of matches and in this fashion it is possible to give a small quantity of matches if the occasion arises. It is just as easy to give a standard or larger quantity should this be necessary.

In Figs. 5 and 6 another embodiment of the invention has been disclosed wherein novel means is shown for holding the sections together in manually segregateable fashion. More particularly, according to this form of the invention, the sections 20 of the bar of matches are separate from each other and held together in a unit by an external sheet of thin material 21 pasted upon the cover portion of the package bar. Each of the detachable sections 20 comprises match stock consisting of a base portion 10^a and match portions 10^b. Each of the detachable sections includes a cover section 11' which has its lower end bent over the base portion 10^a and secured in position with the staple 12. Chemical substance 13 is upon the outer face of the covering 21 located upon the turned up portion of the cover. The covering material 21 may be tissue paper and its function is to hold the various sections of the match package bar together in a unit. Niches 14 are formed along the bent portion of the cover at the bottom so as to facilitate tearing of the holding sheet 21 to segregate the sections.

It is to be understood that perforations, dents, cuts, grooves or any other type of scoring may be used in connection with my match package bar.

It is also to be understood that all niches 14

may be omitted from the book match bar if so desired.

While I have illustrated and described the preferred embodiment of my invention, it is to be understood that I do not limit myself to the precise construction herein disclosed and the right is reserved to all changes and modifications coming within the scope of the invention as defined in the appended claim.

Having thus described my invention, what I claim as new, and desire to secure by United States Letters Patent is:—

In a book match bar, a unit of match stock comprising a plurality of base strip portions integral with a plurality of small groups of match portions projecting therefrom, a cover strip for the match stock consisting of a plurality of separate sections each having an upturned portion bent around the lower portion of the match stock, a back portion extending across the back of the match stock, and a front portion with the free edge thereof engageable beneath the free edge of said upturned portion, chemical substance for aiding in igniting the matches on the front of the upturned portion, a staple for each separate section and engaging through the upturned portion, the base strip, and the back portion of the cover strip, and thin fragile material adapted to be readily torn pasted on the entire surface of the cover strip to hold the sections thereof detachably together in a unit.

MAURICE POLACSEK.
